(57) **CLAIM**

The ornamental design for a thigh high foot thong, as shown and described.

DESCRIPTION

FIG. 1 is a left perspective view of a thigh high foot thong showing our new design;

FIG. 2 is a top, right perspective view thereof;

FIG. 3 is a top, left perspective view thereof;

FIG. 4 is a rear, right perspective view thereof;

FIG. 5 is a bottom, left perspective view thereof;

FIG. 6 is a rear perspective view thereof; and,

FIG. 7 is a right perspective view thereof.

The broken lines of the human leg and foot are for the purpose of illustrating environment and form no part of the claim.
